(57) **CLAIM**

The ornamental design for an electrical switch plate as, shown and described.

DESCRIPTION

FIG. 1 is a perspective view of an electrical switch plate showing my new design;

FIG. 2 is a front view thereof which is an accurate representation of the rear view thereof;

FIG. 3 is a front view thereof;

FIG. 4 is a side view thereof, the opposite side being a mirror image;

FIG. 5 is a perspective view of a second embodiment of my new design;

FIG. 6 is a front view thereof which is a mirror image of a rear view thereof;

FIG. 7 is a front view thereof; and,

FIG. 8 is side view thereof, the opposite side being a mirror image.

The rear of each electrical switch plate is not visible in use.
